LIGHT SHIELD

Edward C. Hemphill and Elsie M. Hemphill,
San Francisco, Calif.

Application July 20, 1940, Serial No. 346,582

1 Claim. (Cl. 2—15)

The present invention relates to eye shields and particularly to those eye shields which are designed primarily to exclude light rays from the eyes so that a person sleeping may rest undisturbed even in daylight. It also has particular usefulness in protecting the eyes from the various kinds of lights which have therapeutic usefulness and which might damage eyesight unless the eyes were protected in some way.

The present invention is in the nature of an improvement over our Patent No. 1,924,315, of August 29, 1933.

It is among the objects of the present invention to provide a simple inexpensive device of this nature which can readily be placed in position and removed by the wearer and which, after being placed in position on the wearer, will remain without becoming dislodged under usual conditions of wear.

One of the principal objects of the invention is to exclude light rays of various kinds, but it should be borne in mind that in the excluding of such rays, or for any other purpose, it should fulfill its function without damage or injury to the eyes or injury of any kind. In numerous instances in the shields of the prior art, the arrangements are such that there is too much pull by the means used to hold the shield in place or the pressures are not properly distributed so that there is pressure on the optic nerve, as well as other discomfort. Such pressures are extremely detrimental and damaging even though so slight as to almost be unnoticeable. The shield of this invention is so designed and constructed that it will not cause any injury or undue pressure because of its being worn.

The comfort of the wearer is also important. Therefore, it is among the objects of the present invention to provide a device constructed of substantially porous material, permitting circulation of air, and so prevent perspiration or any discomfort in use.

Likewise, a device of this character must be so shaped as to conform comfortably with the varying contours of the profile of the user public. The present invention has for an object the provision of such a device which is acceptable for universal use in the accomplishment of its principal function. The design likewise is scientifically constructed to prevent any possible contact of the eyelids no matter what form the profile of the user may be.

A further object of the present invention is to provide a light shield which is simple in de-

sign and construction and therefore may be economically manufactured and supplied.

Referring now to the drawing which is merely illustrative of the present invention:

Fig. 1 is a view of one of the devices in position upon a wearer.

Fig. 2 is likewise a view of one of the devices on the head of a wearer showing a variant form of the holding means.

Fig. 3 is a view of one of the devices in position on a user with another variant form of the holding means.

Fig. 4 is a rear elevational view of the device.

Fig. 5 is a fragmentary sectional view in an enlarged scale taken on the line 5—5 of Fig. 4 and looking in the direction of the arrows.

Referring now to the drawing in more detail, in which like numerals have been used to indicate like portions in the several drawings, the numeral 10 indicates the main or body portion of the light shield, which is preferably of the shape indicated. It is preferably made of several materials which combine to form a light impervious structure. It is preferable to make the background 11 and the outer covering 12 of material impervious to light, such as satin, sateen and the like, which present an attractive finish as well as accomplishing the result desired. While color is not of first importance, nature intended humans to sleep in darkness and therefore it is preferable to use black which indicates or suggests night. The device 10 is preferably provided with a stiffener 13 between the background 11 and the outer covering 12. This stiffener 13 may be of any suitable material such as willow board, etc., but is preferably pliable rice cloth, which is roughly woven so as to bend frequently without breaking. It is to be remembered that the device 10 should be light in weight and yet sufficiently strong so that it will hold its form in shape in use even though the wearer is asleep and bodily movements are not under conscious control. The background 11, the stiffener 13, and the outer covering 12 are held together in any suitable way and a mild use of adhesives is recommended.

The shape of the device, as previously stated, is substantially that shown in Fig. 4, and is so constructed and shaped that the two lobular portions 14 and 15 are adapted to set over the eyes and around the eye socket without contact with either the eye or the eyelashes or any pressure on the optic nerve. A central portion is cut out as at 16 in order to accommodate space for the bridge of the nose.

The device is likewise provided with pads 17 and 18. Pad 18 is preferably made of a properly shaped piece of cloth and stuffed with down 20 or other lightweight porous material, which will permit not only the circulation of air underneath the light shield when in use, but which will readily conform itself under the slight pressures of the holding means to the shape of the wearer around the bridge of the nose and at the lower portion of the eye socket or in the general area of the cheek bone. Thus, no matter the particular peculiarity of the shape of the face, including the nose and cheek bones of the wearer, there will be no contact with or pressures upon either the eyes themselves, the optic nerve or the eyelashes, causing any sort of discomfort or damage. At the same time, the pad 18 by conforming to the contours of the face of the wearer keeps the light from entering the lower edge of the shield.

Pad 17 is provided to secure better circulation of the air and perhaps more comfort for the wearer. It is constructed of a single piece of cloth and is stuffed with any suitable material 20 similar to that described for pad 18.

In the construction of pads 17 and 18 it will be noted that the pads are usually formed by folding the material back on itself and stuffing. The free edges which coincide due to the folding, being 21 and 22, 23 and 24, respectively, are held in place on the device by means of stitching 25 or, in some instances, may even be held there by adhesives of any suitable design. In Fig. 5 there is shown a sectional detail which indicates that the three layers of material which form the main or body portion 10 are held together at the periphery by a binding 26 which laps over on both front and rear sides and stitched as indicated 25 just inside the periphery, thus passing through all of the layers forming the main or body portion 10. In so doing it is preferable, as shown in Fig. 5, to take the free edges of the pads 17 and 18 and have the peripheral binding pass over them in position so that the stitching 25 will hold the pads in place and cover the free edge, making a neat and finished looking product.

In such a manner the main or body portion 10 is preferably constructed.

The method of holding this light shield in place when being used is shown in preferred form in Fig. 1. There are loops 27 at either side of the device 10, which are preferably of elastic material which will stretch without too much pull. These loops 27 are retained on the main body portion in any suitable way and in the preferred form they are shown as being clipped in place by clips or fastenings 28. However, it is to be un-

derstood that any suitable means, such as sewing, glueing, threading, etc. may be used. The loops 27 pass through a looped or lapped portion 30 of the band 31 which may extend to the back 5 of the head of the wearer. This band may be formed of any suitable material such as a flexible lightweight tape, elastic or the like. It is adjustable in lengths by means of the slip clip 32 or by any other suitable means for accomplishing this result comfortably. It is to be noted that the elastic loops 27 are slideable relative to the band 31, so that the band 31 can be shifted along the loops until brought into comfortable and proper position on the wearer.

When the elastics of the loops 27 are new and tight the device itself may be worn as shown in Fig. 2 with the band 31 above the ears. When the elastic is old, or preferably when comfort and correct position are required, the device is worn as shown in the preferable view, Fig. 1.

In Fig. 3 there is shown a further variant form of holding the light shield in position which is cheaper in construction and yet permits the correct and preferred position shown in Fig. 1. The precise positioning accomplished by wearing the device with the loops over and under the ear, without any pressure on the back of the ear, may be accomplished by having the elastic loops 27a extend from the top portion of the lobe 14 to the bottom portion of the lobe 15 (and vice versa) and cross at the back of the head of the wearer, as shown at 33 in Fig. 3. This positioning may be accomplished by also having the loops 27 extend clear to the back of the head of the wearer and joining them by any suitable means at the point 33 or any other convenient place.

It is contemplated that changes of form may be made with variation and departures from the illustrated forms, without departing from the scope of this invention. Such variations and departures include those made possible by discovery of improved materials and by uses and forms of present materials as well as improved practices and results which may be possible in commercial fabrication and handling.

We claim:

A light shield, including a light excluding body portion adapted to cover the eyes of the wearer without contact with any portion of the eyes, and resilient loops extending from the upper portion on one side to the lower portion on the opposite side and vice versa, for holding said shield in place so that the respective loops will extend over and under the ears of the wearer without any pull on the back of the ears.
